UNITED STATES PATENT OFFICE.

HARRY FRISCHER, OF NEW YORK, N. Y.

DESIGN FOR A PLAITED FABRIC.

Application filed December 12, 1922. Serial No. 4,577. Term of patent 14 years.

To all whom it may concern:

Be it known that I, HARRY FRISCHER, residing at New York, in the county and State of New York, have invented a certain new, original, and ornamental Design for a Plaited Fabric, of which the following is a specification, reference being had to the accompanying drawing, forming part thereof.

Figure 1 is a plan view of my new design, as shown.

Figure 2 is an edge view, looking at the fabric in one direction.

Figure 3 is an edge view, looking at the fabric in a direction at right angles to Fig. 2.

Referring to the drawings, the fabric is plaited in one direction, and in a direction at right angles to the pleats is provided with a plurality of raised portions separated by depressed portions, thus producing a wavy effect upon the plaited fabric in a direction at right angles to the pleats.

I claim:

The ornamental design for a plaited fabric, as shown and described.

HARRY FRISCHER.
